UNITED STATES PATENT OFFICE

BENNO F. JANCKE, OF BROOKLYN, NEW YORK, ASSIGNOR TO TOWNSEND MANUFACTURING COMPANY, INC., OF NEW YORK, N. Y., A CORPORATION OF NEW YORK

CLIP

Application filed December 13, 1928. Serial No. 325,750.

This invention relates to clips, particularly of the kind used in closing a wrapper around a strand of hair on a curling rod prepared for permanent waving, and provides improvements therein.

The invention provides a clip of the character described which is readily manipulated in the operation of applying it around and removing it from a wrapper. It further provides a simple and readily manufactured device.

An embodiment of the invention is illustrated in the accompanying drawings, wherein:

15 Figure 1 is a plan view (with parts broken away) in the open position.

Fig. 2 is a plan view, in the closed position.

Fig. 3 is an enlarged sectional view on the line III—III, Fig. 1.

20 Fig. 4 is a view showing the device applied around a wrapper such as used in permanent waving of hair.

Fig. 5 is a view looking at the side or edge of the device from the right, in respect to

25 Fig. 2.

Referring to said drawings, numerals 10 and 12 designate a pair of jaws, hinged as indicated at 14.

The jaws 10 and 12 are preferably composed of crescent-shaped disks. These disks are conveniently made of sheet material, of any desired or suitable character. One of said jaws, as 12, is preferably composed of a pair of said disks 16 and 18, the other jaw 20 being composed of a disk 20 adapted to enter between and lap said disks 16 and 18 in closed position, as shown in Fig. 2.

The disks 16 and 18 are conveniently spaced apart by strips 22, 23 placed between said disks near their outer edge.

Means 25 are provided for holding the jaws in closed position. This means is preferably in the form of a spring catch, preferably in the form of a loop 27 running across the outer faces of the disks 16, 18, secured at one end to said disks, as by means of a flat staple 29 passing over one end piece of said loop, through said disks 16, 18, and preferably also through the strip 22. The ends of the staple 50 are preferably curled over the other end piece

of said loop 27, as shown most clearly in Fig. 3. The free end of loop 27 is preferably confined in a notch 31 in the free end of jaw 12, limiting the resilient swinging movement thereof in both directions. The free end of jaw 10 collides with the free end of the loop 27 (forming the spring catch) as the jaws 10 and 12 come together or lap, as in closing the jaws together around a wrapper, and as the jaws 10 and 12 are further pressed together the loop 27 is pressed back, reacting against the edge or rim of the jaw 10, and holding the jaws against movement in the opposite direction (opening). The rim of the free end of jaw 10 is preferably notched as indicated at 33 to provide a positive hold of the loop (catch) on said rim. Between its point of attachment 29 and its point of engagement with rim of jaw 10, the spring-catch or loop 27 is preferably straight, so that the pull on the staple 29 is in a straight line and there is substantially no "give" in the jaws when once closed and caught by the catch 27.

A spring 36 is preferably provided for reacting on said jaws in a direction to force them apart, whereby said jaws will open under the action of said spring when released by the spring catch 27. The spring 36 is preferably in the form of a coil-spring, located around a pin 38 forming the hinge or pivot of said jaws 10 and 12 and between two of the disks 18 and 20 forming said jaws. The spring 36 is preferably coiled and while under tension, its ends 40, 41 fastened to said disks. The fastening is conveniently effected by bending the ends 40, 41, of spring 36 at right angles to the plane of the coil and inserting these in holes or recesses formed in said disks 18 and 20, as shown most clearly in Fig. 3.

A space 45 is preferably provided between disks 18 and 20 to prevent binding of said spring 36. For this purpose the pin 38 is conveniently provided with a shoulder 48 at a distance beyond the face of the disk 20 somewhat greater than the thickness of the spring, and the other disk 18 rests against this shoulder 48. The pin 38 conveniently is upset at 100

one end and headed at the other to hold said disks and pin together.

The jaws 10 and 12 are conveniently provided with handles 51, 52 for pressing the jaws together, and a projection 53 is conveniently provided on spring catch 27 for convenience in manipulating the same to release the jaws.

Operation.—The jaws 10 and 12 are closed together around a wrapper enclosing a strand of hair (for example), by pressing on the handles 51, 52, for example. The spring catch 27 automatically engages the notched rim of the jaw 10 and thereby holds the jaws in closed position. The straight spring catch prevents "give" in the connection.

To open, the spring catch 27 is pressed away from the notched rim, and the jaws moved apart, or where spring 36 is used, the reaction of the spring causes the jaws 10 and 12 to spring apart when said catch 27 is released.

The invention may receive other embodiments than that herein specifically illustrated and described.

What is claimed is:—

1. A clip comprising a pair of hinged jaws adapted to be closed together around a wrapper, a spring reacting to force said jaws apart to open position, and means for holding said jaws in closed position against the force of said spring, said holding means comprising a spring catch mounted on one jaw and adapted to engage the other jaw, said spring catch being a loop running straight across one of said jaws and adapted to engage the outer rim of the other jaw.

2. A clip comprising a pair of hinged jaws adapted to be closed together around a tubular wrapper, said jaws comprising overlapping semicircular disks, a spring between said disks reacting to force said jaws apart to open position, and means for holding said jaws in closed position against the force of said spring, one of said jaws comprising a pair of spaced disks, and receiving the other disk between them, said hinge comprising a stud having a shoulder thereon adapted to hold one of the outside disks spaced from the intermediate disk, and providing a space for the free action of said spring; said spring being arranged around said stud in said space.

3. A clip comprising a pair of semi-circular jaws comprising disks hinged at one end on an axis passing through the plane of the disks and having semi-circular notches approximately midway thereof in the edge portions thereof facing one another, adapted in the closed position of the jaws to surround and grip a wrapper, said jaws constituting levers of the second class, means for fastening said disks in closed position around a wrapper, and a spring extending from one disk to another disk on the opposite side of the

pivotal axis of the disks, and acting on said disks in the manner of the resisting force on levers of the second class, said spring bearing against said opposite disks and reacting thereon to normally force said disks apart when said disks are not held by said fastening means.

In witness whereof, I have hereunto signed my name.

BENNO F. JANCKE.
